UNITED STATES PATENT OFFICE.

GEORGE A. BOYDEN, JR., AND JOHN C. BOYDEN, OF BALTIMORE, MARYLAND.

RAILWAY-CAR TRUCK.

1,341,781.

Specification of Letters Patent. Patented June 1, 1920.

Application filed April 6, 1920. Serial No. 371,664.

To all whom it may concern:

Be it known that we, GEORGE A. BOYDEN, Jr., and JOHN C. BOYDEN, citizens of the United States, residing at Baltimore, in the 5 State of Maryland, have invented certain new and useful Improvements in Railway-Car Trucks, (Case F;) and we do hereby declare the following to be a full, clear, and exact description of the invention, such as 10 will enable others skilled in the art to which it appertains to make and use the same.

Our invention relates to railway car trucks.

Our application for U. S. Letters Patent 15 for railway car trucks, Case A, which was filed May 22nd, 1919, and serially numbered 298953 involves a truck comprising members that act coördinately horizontally so that the wheels and journals will conform to the 20 contour of the rails whatever it may be, and which, in addition, have disparate vertical actions.

Our application for U. S. Letters Patent 25 for railway car trucks, Case B, which was filed August 5th, 1919, and serially numbered 315427 involves a truck comprising members that act coördinately horizontally as in the truck shown in Case A, and which, in addition, have equalized vertical actions.

30 The present application is intended to cover a truck comprising members that act coördinately horizontally as in the truck shown in Cases A and B, and which, in addition, have equalized vertical actions as in 35 the truck shown in Case B.

Among the objects of our invention are:—

To simplify the various members of the truck.

40 To produce a truck the members of which can be assembled or separated without the use of tools.

To produce a truck having a member 45 which acts to coördinate the mutual angularity of the axles in a horizontal plane and at the same time serves to transmit the load stress to the members through springs.

50 To provide means for connecting the pilot and trailer bolsters to the central bolster so that the former may have horizontal and vertical freedom with reference to the latter.

One embodiment of our improved truck is shown in the accompanying drawings, in which:—

55 Figure 1 is a plan view of the truck constructed in accordance with our invention.

Fig. 2 is a side view of the truck shown

in Fig. 1, said view being shown partly in section and the section being taken as along the line 2—2 in Fig. 1 looking in the direction of the arrows.

60

Fig. 3 is a view of the coördinating plate taken as viewed in the direction of the arrow 3 in Fig. 2.

Fig. 4 is a side view of either the pilot or trailer bolster.

65

Fig. 5 is a view of the bolster shown in Fig. 4 looking in the direction of the arrow 5 in said figure.

Fig. 6 is a plan view of the central bolster.

Fig. 7 is a view of the bolster shown in Fig. 6 looking in the direction of the arrow 7 in said figure.

70

Fig. 8 is a view of the bolster shown in Fig. 6 looking in the direction of the arrow 8 in said figure.

75

Fig. 9 is a plan view of the spring cap.

Fig. 10 is a view of the cap shown in Fig. 9 looking in the direction of the arrow 10 in said figure.

80

Throughout the specification and claims, a longitudinal movement or stress will be that in the direction of the length of the rails, and a transverse movement or stress will be that in a direction transverse to the rails.

85

In the drawings:—

15 represents the wheels, and 16, 17 and 18 represent, respectively, the pilot, central and trailer axles. The journals of the axles are mounted in any approved form of axle 90 box such as 19, and the axles and wheels are of Master Car Builders' construction.

Each pilot and trailer bolster consists of a pair of pedestals such as 20, each pedestal being provided with jaws 21 for the reception 95 of the axle box 19 which fits snugly therein. The pedestals 20—20 of each end

member are joined together by the frame 22 and said frame is provided with arms 23—23 terminating in the boss 24 having a hemispherical lower surface. The frame 22 is provided with two spring bases 25—25 and with ears 26 for the support of brake shoes. The brake shoes forming no part of our 100 present invention are not illustrated or described. The frame 22 is provided with a pair of rocker bearings 27—27 each having end surfaces 29 and side surfaces 33—33.

105

The central bolster consists of a pair of pedestals such as 30—30, each pedestal being provided with jaws 31 for the reception 110 of the axle box 19 which fits snugly

Fig. 1 is a plan view of the truck constructed in accordance with our invention.

Fig. 2 is a side view of the truck shown

therein. The pedestals 30—30 of the central members are joined together by the frame 32 and said frame is provided with ears for the support of brake shoes. The 5 brake shoes forming no part of our present invention are not illustrated or described.

The frame 32 is provided on each side with a pair of sockets 34—34 having hemispherical bottoms. One of the bosses 24 is 10 introduced in each of the sockets 34 and serves to connect the corresponding end member with the central member. The frame 32 is provided with six finished surfaces 36 on the inner surfaces thereof for a 15 purpose hereinafter explained.

It is to be noted that each end member is connected with the central member on the side of the latter adjacent to said end member. It is furthermore to be noted that by 20 reason of the shape of the boss 24 and the socket 34, each end member, in addition to revolving in a horizontal plane around the axis of said socket, can move angularly in vertical planes. Thus, the articulation of 25 each end member with the central member is substantially a universal joint.

The coördinating plate 37 is provided with four bearings 35 the ends of which are curved as at 38. The bearings 35 extend 30 within the rocker bearings 27 of the pilot and trailer bolsters, the surfaces 38 being in contact with the end surfaces 29 of said rocker bearings. The bearings 35 rest upon the spring caps 40 and the latter rest upon 35 the top of the springs 39. The caps 40 are provided with guides 41—41 which slide freely upon the side surfaces 33 of the rocker bearings 27—27.

The king pin 42 is connected to the car 40 body in any approved manner and any approved form of side bearings are secured upon said body to form a sliding bearing upon the truck side bearings 43.

The coördinating plate 37 is provided 45 with six gibs 44 finished on the outer surface thereof, which project downwardly and each has a sliding bearing upon one of the finished surfaces 36 of the frame 32, thus connecting the coördinating plate and the central bolster together in such a manner that while the former can have angular movements in a 50 vertical plane and vertical and transverse movement with reference to the latter, yet the latter is forced to partake of the angular movement in a horizontal plane of the former.

Each of the bearings 35 of the coöordinating plate 37 may have vertical and longitudinal movements as well as angular movements 60 within the corresponding rocker bearing 27.

The truck members act coördinately horizontally according to the method set forth in Case A, with the exception that each pilot 65 and trailer bolster is joined by a ball and

socket joint to the central bolster on the near side thereof. This construction has been adopted in the truck shown in the present application in order to provide for a slightly different relative angular movement 70 of said members from the movement of the corresponding members shown in Case A.

The coördinating plate 37 has a fixed vertical relation to the car body, but it may swing angularly about the king pin 42. 75

Movements of the end and central bolsters with reference to the coördinating plate which are permitted by the resilience of the springs 39 and the ball and socket joints insure the utmost freedom of the wheels in 80 following the vertical contour of the rails.

As set forth in Case A, the coördinating horizontal movements of the members provide for the utmost freedom of the wheels 85 in following the horizontal contour of the rails.

Thus, the truck illustrated and described in this case provides for the minimization of the friction due to the vertical and transverse stresses against the rails and thus insures a minimization of the longitudinal stress against the draw bar, which eventuates in a great reduction of operating costs. 90

We claim:—

1. In a six wheel truck for railway transportation, the combination with three journal members, each end member being connected to the near side of the central member by a ball and socket joint, whereby each end member moves only angularly about 100 said joint. 95

2. In a six wheel truck, the combination with a bolster for each pair of journals, a coördinating plate engaging with the central bolster and with each of the pilot and trailer 105 bolsters to control the mutual angularity of said journals, springs between said coördinating plate and said pilot and trailer bolsters and a ball and socket joint between each of said pilot and trailer bolsters and 110 said central bolster.

3. In a six wheel truck, the combination with a bolster for each pair of journals, a coördinating plate engaging with the central bolster and with each of the pilot and trailer 115 bolsters to control the mutual angularity of said journals, springs mounted on said pilot and trailer bolsters and cap plates mounted on said springs, said cap plates having sliding connections with said pilot and trailer 120 bolsters and with said coördinating plate.

4. In a six wheel truck, the combination with a rigid structure subjected to the vertical load stress, of pilot, trailer and central bolsters articulated together, springs on said 125 pilot and trailer bolsters, cap plates on said springs and sliding engagement between said cap plates and said structure, transverse to the direction of said stress.

5. In a six wheel truck, the combination 130

with a bolster for each pair of journals, of a coördinating plate engaging with the central bolster, rocker bearings on the pilot and trailer bolsters comprising end surfaces, and 5 bearings on said coördinating plate having curved surfaces to engage said end surfaces.

6. In a six wheel truck, the combination with a bolster for each pair of journals, of a coördinating plate engaging with the central bolster, rocker bearings on the pilot and trailer bolsters comprising end and side sur- 10

faces, bearings on said coördinating plate having curved surfaces to engage said end surfaces, springs on said pilot and trailer bolsters and cap plates on said springs en- 15 gaging said side surfaces and the bearings of said coördinating plate.

In testimony whereof, we affix our signatures.

GEORGE A. BOYDEN, JR.
JOHN C. BOYDEN.
